No. 760,644.

PATENTED MAY 24, 1904.

P. E. NEWSOM,
TIME GAS LIGHT EXTINGUISHER.

APPLICATION FILED OCT. 27, 1903.

NO MODEL.

UNITED STATES PATENT OFFICE.

PHILIP E. NEWSOM, OF BROOKLYN, NEW YORK.

TIME GAS-LIGHT EXTINGUISHER.

SPECIFICATION forming part of Letters Patent No. 760,644, dated May 24, 1904.

Application filed October 27, 1903. Serial No. 178,680. (No model.)

To all whom it may concern:

Be it known that I, PHILIP E. NEWSOM, residing at Brooklyn, in the county of Kings and State of New York, have invented certain new and useful Improvements in Automatic Apparatus for Extinguishing Lights, of which the following is a full, clear, and exact description, such as will enable others skilled in the art to which it appertains to make and use the same.

My invention relates to an apparatus for automatically extinguishing a gas-light at a predetermined time, although it may be used for extinguishing other kinds of lights. It has for its object to provide a simple inexpensive device of this character that will operate easily and surely. Other objects will appear from the hereinafter description.

The invention consists in certain novel features of construction and combination of parts, all as hereinafter fully set forth in this specification, and particularly pointed out in the claims thereof.

Referring to the drawings, which form a part of this specification, and in which the same reference characters represent the same parts in the different views, Figure 1 is a rear view of the apparatus attached to a swinging or center gas-fixture. Fig. 2 is a section on the line 2 of Fig. 1. Fig. 3 is a section on line 3 of Figs. 1 and 2. Fig. 4 is a detailed sectional view, on an enlarged scale, of certain parts of the mechanism for automatically extinguishing the light, this section being taken on the line 4 of Fig. 1. Fig. 5 is a detail view of certain parts illustrated by Fig. 4, some of the parts being in a different position from that shown in Fig. 4. Fig. 6 is a front view of certain parts shown in Figs. 4 and 5. Fig. 7 is a detailed sectional view on the line 7 of Fig. 1, showing certain parts of the mechanism for extinguishing the light and means for starting and stopping said mechanism. Fig. 8 is a front view of certain parts of the mechanism shown in Fig. 7, taken on the line 8 of that figure.

The part marked 1 on the drawings represents the gas-pipe of the swinging gas-fixture. 2 is the burner, and 3 is the valve by which the gas passing through the pipe is turned on and off from the burner.

4 is the casing, secured to the gas-fixture. Mounted in this casing is an arbor 5, the upper end of which is bifurcated and connected to the valve 3. The lower end is journaled in the lower part of the casing 4, this end passing through the casing and having secured thereto the lever 6. 55

7 is a coiled spring, the inner end of which is secured to the arbor, and the outer end is secured to one side of the casing by a screw 8, as shown in Fig. 2.

9 is a stop or pin projecting from the lower end of the casing and against which the lever rests when the apparatus is not set for extinguishing the light. When the lever is turned 60 from the pin, it turns the arbor and winds or puts the spring under tension. Pivoted to the rear side of the casing 4 and projecting downwardly therefrom is a swinging stop 10, which is recessed at 11, leaving a finger 12 70 thereon, which holds the lever 6 in a set position, with the spring which operates the arbor 5 under tension.

13 is a stop which rests against a finger or arm to be hereinafter described. 75

14 represents the casing of the clock mechanism shown in rear view of Fig. 1, which is suspended from the gas-fixture by the straps or rods 15.

16 represents what corresponds to the ordinary alarm dial-clock, having a finger or pointer 17 secured to the arbor 18. Secured to the front end of this arbor is a small disk 19, having a projection or finger 20 thereon. 21 is a gear-wheel loosely mounted on this arbor and which has a collar 22, which is thrown over the disk 19. When this gear-wheel is turned to a certain position, the pin 20 of the disk 19 bears against the forward edge of the collar until the gear-wheel is 80 moved to such a position by the clock mechanism that the cam-recess 23 in the collar comes opposite the pin 20, when the gear-wheel and collar are thrown over the disk. 85

24 is a spring secured to the forward frame 95 25 of the clock mechanism. This spring rests against the inner face of the gear-wheel 21 and tends to move the gear-wheel forward or laterally on the arbor 18. The inner end of this spring is inturned, forming a finger 26. 100

27 is a shaft or arbor pivoted into the front and rear frames 28 and 29 of the clock mechanism. 30 is a finger secured to this arbor, and 31 is an arm also secured to the arbor 5 and carrying a weight 32, which moves the arbor in a certain direction. 33 is another arm secured to this arbor, the free end of the frame being bent at right angles and extending through the slot 34 in the rear face 10 of the clock and against which the end 13 of the arm 10 rests when the mechanism is set. The finger 26 of the spring 24 comes in the path of movement of the finger 30 and holds the arbor 27 in a set position to be described.

15 This apparatus operates as follows: Suppose, for example, it is desired to extinguish the light at twelve o'clock. The arbor 18 is turned until the hand 17 points to the hour "12," as shown on Fig. 1 of the drawings. As the 20 arbor is moved it carries with it the disk 19, carrying the finger 20, which forces the gear-wheel 21 inwardly, thus forcing the finger 26 of the spring 24 over the arm 30, so that this arm cannot be moved upwardly or the arbor 25 27 rock, the arm 33 being in the position shown in Fig. 1 of the drawings. The clock mechanism is now set. The lever 6 has moved from its stop 9 for winding up its spring, and during this operation the spring on the arbor 30 5 is wound up. The free end of this lever strikes against the swinging arm 10 and moves it into the position shown in dotted lines in Fig. 1. Then the lever is released, and the free end moves in the recess 11 of this arm. 35 The swinging arm moves backward against the arm 33 and is held in position against further movement by this arm 33. The finger 12 prevents the lever 13 from moving back to its original position. The parts are now as 40 shown in Fig. 1 and the gas-valve turned so that the gas can pass through the gas-pipe to the burner 2. At twelve o'clock the gear 21 has been moved by the clock mechanism to such position that the cam-recess 23 therein will 45 be opposite the finger 20 of the disk 19, at which time the spring 24 throws the gear forward, and the finger 26 is carried out of the way of the arm 30. At this time the arm 33 no longer holds the swinging arm set when 50 the lever 6 is released, and the coiled spring 7 turns the arbor 5, whereupon the valve 3 is turned to cut off the gas.

The means for starting and stopping the clock mechanism will now be described.

55 40 is the arbor of the clock mechanism, to one end of which the hair-spring 41 is secured, 42 being the balance-wheel mounted on the arbor. This balance-wheel has also secured to it the pin 43, which meshes with the teeth 60 on the lever 44, mounted on the escapement-arbor 55, the escapement-lever being shown at 46, which is in contact with the escapement-wheel 47, mounted on the arbor 48. This arbor has secured to it the pinion 49, 65 which is driven by a train of gears leading to

the mainspring. (Not shown.) Secured to the rear frame 29 of the clock mechanism is a spring 51, having an inturned end of finger 52, which is normally out of contact with the lever 44.

70 53 is a push-button extending through the rear casing of the clock and through the frame 29 and has an eye 54 on the forward end thereof, through which the spring 51 passes. When it is desired to stop the clock mechanism, this 75 push-button is pushed inwardly, when the free end 52 of the spring is thrown in contact with the lever 54 and holds the lever from rocking and prevents the escapement-arbor from rocking, whereby the clock mechanism is stopped from operating. When the push-button is released, the lever is permitted to rock in the usual manner. If the mainspring 80 of the clock mechanism is wound, but the mechanism is not operating when the button 85 is moved in and released quickly, the finger 52 of the spring will strike the lever 54 and rock the lever, whereupon the escapement-arbor is rocked and the mechanism is put in motion.

90 Having described my invention, what I claim as new, and desire to secure by Letters Patent, is—

1. In a device of the class described, a 95 burner, an extinguisher connected to said burner, an arbor having one end thereof connected to the extinguisher, a spring connected to the arbor and adapted to move the arbor to operate the extinguisher to extinguish the light, a lever connected to the arbor, a 100 clock mechanism, an arm carried thereby and adapted to hold the arbor against the tension of the spring, said arbor adapted to be released when the clock mechanism reaches a certain point.

105 2. In a device of the class described, a burner, an extinguisher for the burner, an arbor one end of which is connected to the burner, a lever on the other end of the arbor, a spring connected to the arbor adapted to move the arbor in a position to operate the extinguisher to extinguish the light, a pivoted arm adapted to hold the lever against the tension of the spring, having a downwardly-projecting finger for engaging the said lever and holding the arbor against the tension of the spring, means connected to a clock for holding said arm in a fixed position, and a clock mechanism adapted and arranged to release the arm at a predetermined time.

110 3. In an apparatus of the class described, a burner, an extinguisher for the burner, an arbor having one end thereof connected to the burner, a lever on the other end of the arbor, a spring connected to the arbor and adapted to move it in a certain position whereby the extinguisher is operated to extinguish the light, a stop to limit the movement of the lever in one direction, a catch for holding the lever in another direction against the tension 115

of the spring on the arbor, means carried by the clock for holding said catch and means for permitting the catch to be released at a predetermined time, whereupon the lever is released and the arbor operated under the tension of the spring and the extinguisher is moved to extinguish the light.

4. In an apparatus of the class described, a burner, an extinguisher for the burner, an arbor having one end thereof connected to the burner, a lever on the other end of the arbor, a spring connected to the arbor and adapted to move it in a certain position whereby the extinguisher is operated to extinguish the light, a stop to limit the movement of the lever in one direction, a catch for holding the lever in another direction against the tension of the spring on the arbor, means connected to a clock for holding said catch, means for permitting the catch to be released and the arbor to be operated under the tension of the spring and the extinguisher to be moved to extinguish the light, and a clock mechanism adapted to release the catch at a predetermined time.

5. In an apparatus of the class described, a burner, an extinguisher for the burner, an arbor connected to said extinguisher, a spring adapted to move the arbor whereby the extinguisher is operated to extinguish the light, a lever connected to the arbor, an arm pivoted adjacent to the lever, said arm having a finger for holding the lever, a pin for holding the arm and means for releasing the pin at a predetermined time.

6. In an apparatus of the class described, a burner, an extinguisher for the burner, an arbor connected to said extinguisher, a spring adapted to move the arbor whereby the extinguisher is operated to extinguish the light, a lever connected to the arbor, an arm pivoted adjacent to the lever, said arm having a finger for holding the lever, a pin carried by a clock for holding the arm and a clock mechanism for moving the pin to release the arm at a predetermined time.

7. In a device of the class described, a gas-burner, a valve for turning on and cutting off

the supply of gas to the burner, a casing mounted adjacent to the burner, an arbor mounted in said casing one end of which is connected to the valve, a spring connected to the arbor to turn the valve to cut off the supply of gas, a lever connected to the arbor, an arm pivoted to the casing, said arm having a recess and a finger, the recess adapted to receive the end of the lever and the finger to prevent the lever from moving under the tension of the spring of the arbor, a clock mechanism, an arm carried thereby and adapted to engage the arm pivoted to the casing to hold the pivoted arm and the lever against the tension of the spring and means for releasing the arm of the clock mechanism at a predetermined time, whereby at such time the valve is turned to cut off the supply of gas to the burner.

8. In an apparatus of the class described, a clock mechanism, a shaft mounted therein, said shaft carrying a disk on one end, said disk having a finger connected thereto, a gear loosely mounted on the shaft and adapted to be driven by the clock mechanism, means on the gear adapted to be controlled by the finger of the disk, a spring adapted to be controlled by the position of the gear, a rock-shaft having a finger thereon controlled by the position of the spring, another arm carried by the shaft, a gas-burner, a valve for the burner, an arbor connected to the valve, a spring connected to the arbor and adapted to move it to normally hold the valve in such position as to cut off the supply of gas to the burner and means between the arbor and the last-mentioned arm adapted to be engaged by the arm to hold the valve in such position as to permit a supply of gas to the burner and to be released by the arm when the clock mechanism has reached a predetermined position.

In testimony whereof I affix my signature in the presence of two witnesses.

PHILIP E. NEWSOM.
